(57) **CLAIM**

The ornamental design for a sword, as shown and described.

DESCRIPTION

FIG. 1 is a left side elevational view of the design of the present invention for a sword, of which the right side is a mirror image thereof;

FIG. 2 is a front elevational view of the sword of FIG. 1;
FIG. 3 is a rear elevational view of the sword of FIG. 1;
FIG. 4 is a top plan view of the sword of FIG. 1, of which the bottom plan view is a mirror image thereof;

FIG. 5 is a left side elevational view of an alternate embodiment of the design of the present invention for a sword;
FIG. 6 is a partial left side elevational view of the sword of FIG. 1, showing an enlarged view of the sword handle of the sword, the right, opposite, side of which is a mirror image thereof;

FIG. 7 is a rear elevational view of the sword handle of FIG. 6; and,

FIG. 8 is a top plan view of the sword handle of FIG. 6, of which the bottom plan view is a mirror image thereof.
